UNITED STATES PATENT OFFICE.

MEINE P. FREIBORG, OF DRISCOLL, NORTH DAKOTA.

WASHING DEVICE.

1,082,313.

Specification of Letters Patent.

Patented Dec. 23, 1913.

Application filed July 16, 1913. Serial No. 779,381.

To all whom it may concern:

Be it known that I, MEINE P. FREIBORG, a citizen of the United States, residing at Driscoll, in the county of Burleigh and State of North Dakota, have invented certain new and useful Improvements in Washing Devices, of which the following is a specification, reference being had to the accompanying drawings.

10 This invention relates to certain improvements in washing devices and the object of the invention is to provide a device of this general character having novel and improved means adapted to be employed independently of the receptacle containing the cleansing fluid.

15 The invention consists in the details of construction and in the combination and arrangement of the several parts whereby certain important advantages are attained and the device is rendered simpler, less expensive and otherwise more convenient and advantageous for use, all as will be herein-after more fully set forth.

20 25 The novel features of the invention will be carefully defined in the appended claims.

In order that my invention may be the better understood, I will now proceed to describe the same with reference to the accompanying drawings, wherein—

Figure 1 is a vertical section of my device; and Fig. 2 is a perspective view of the plunger.

Referring more particularly to the drawing, the letter A designates a receptacle adapted to contain water. B my improved washing device, and C the bowl of a cream separator. My improved washing device B comprises a cylinder 5 which is enlarged 35 at its lower end as at 6, the enlarged portion of the cylinder being provided with a plurality of openings 7 near its lower end, which extend entirely around the cylinder. The upper end of the cylinder 5 is provided 40 with a closure cap 8, the cap having a central opening 9 therein for the passage of a rod 10, the upper end of which is provided with a handle 11, and the lower end of which is secured to a plunger 12 which is 45 adapted for reciprocation in the cylinder 5. The bowl C is arranged in the enlarged portion 6 of the cylinder and is supported 50 therein by means of a rod 13 which is passed through diametrically opposite openings 7

below the lower edge of the bowl, the bowl 55 being adapted to rest upon the rod whereby it is prevented from dropping out of the cylinder.

In the practical use of my device, after the bowl has been mounted in the enlarged 60 portion 6 of the cylinder, the cylinder is placed in the receptacle A which is partially filled with water, the free edge of the enlarged portion 6 of the cylinder resting upon the bottom of the receptacle, and the 65 lower edge of the bowl being spaced therefrom. The plunger rod 10 is then moved upwardly so that the plunger 12 is moved upwardly within the cylinder 5, thereby drawing a quantity of water through the 70 bowl into the cylinder 5. When the plunger is moved downwardly the water is again passed through the bowl and into the receptacle through the openings 7, and when this operation is repeated several times the bowl 75 will have been washed perfectly clean.

What I claim is:

1. A device of the character described comprising a cylinder having an enlarged end portion adapted to receive the article 80 to be cleansed, the lower marginal portion of such cylinder being provided with a series of perforations, means removably projected through the lower marginal portion of the enlarged part of the cylinder to support 85 the article to be cleansed within such enlarged part, and a plunger mounted within the cylinder above the enlarged portion thereof.

2. A device of the character described 90 including a cylindrical body having one end open, the marginal portion of the body adjacent its open end being provided with a series of perforations, such open end portion of the cylinder being adapted to accommodate the article to be cleansed, a plunger mounted for reciprocation within the cylinder, and removable means insertable through the marginal portion of the cylinder adjacent its open end to support the article to be 95 cleansed within the cylinder.

In testimony whereof I hereunto affix my signature in the presence of two witnesses.

MEINE P. FREIBORG.

Witnesses:
